[57] ABSTRACT

A plier comprising a pair of crossed arms each of which is provided with two overlying sections composed of a synthetic plastic material. The overlying sections form a recesses in each arm in which a part of the other arm is received and pivotably guided.

FIG. 2

FIG. 1

FIG. 3

FIG. 4

INVENTOR

JOSEF KRAMPE

By: LEWIS S. STARK
Attorney

BACKGROUND OF THE INVENTION

The present invention relates to pliers and more particularly to a plier with arms composed of a synthetic plastic material.

Pliers are well known. They are available in all shapes and sizes and are used for gripping, clamping, cutting and similar tasks. Since a considerable amount of force may have to be exerted on the piece that is being worked on, as for example, in performing a cutting operation, the pliers are usually of metallic construction.

Metallic pliers have certain inherent disadvantages. Not only is the metal expensive but the forming operation and the labor involved is also expensive. Metallic pliers are electrically conductive and if they are to be used near current carrying devices they must be insulated and handled with great care.

SUMMARY OF THE INVENTION

It is therefore a general object of the present invention to provide a plier which is not subject to the disadvantages of the prior art.

A more particular object of the invention is to provide a plier which is inexpensive and safe to use on electric equipment.

The invention is embodied in a plier comprising a pair of crossed arms each of which is composed of two overlying sections. The arms are each provided with a recess wherein a part of one section of each the other arm is received and pivotably guided. Pivot means are provided for connecting the arms at their intersection so as to permit relative pivotal movement of the arms.

The two sections which make up each arm are coextensive, one section is substantially flat and the other section includes a compartmentalized hollow portion and a jaw portion. The sections are composed of a non-metallic substance, preferably an injection-molded synthetic plastic material. The sections are of such proportions that when they are joined to one another they form an arm which exhibits the necessary rigidity that is required of the arm of a plier. Heretofore this rigidity could only be achieved with metallic arms.

The novel features which are considered as characteristic for the invention are set forth in particular in the appended claims. The invention itself, however, both as to its construction and operation, together with additional objects and advantages thereof, will be best understood from the following description embodiment when read in connection with the accompanying drawing.

BRIEF DESCRIPTION OF THE DRAWING

FIG. 1 is a front elevation of a plier according to the present invention;

FIG. 2 is a front elevation of two sections of the plier with the overlying coextensive section omitted for the sake of clarity;

FIG. 3 is a partial view of one arm with the plier; and

FIG. 4 is a partial side view of the arm shown in FIG. 3.

DESCRIPTION OF THE PREFERRED EMBODIMENTS

Referring to FIG. 1 there is shown a plier comprising a pair of crossed arms 1 and 2, which are composed of

two overlying sections 3 and 4 and 3a and 4a, respectively. The sections 3 and 3a and 4 and 4a are coextensive, and the arms are identical. A pivot pin 5 connects the four sections 3 and, and 3a and 4a.

In FIG. 2 the upper section 3 of arm 1 has been removed so that it appears as if the arm 1 had been cut in half. To put it another way, of the arm 1 only the section 4 is shown, overlying coextensive section 3 has been removed; of the arm 2 only the section 4a is shown.

The section 3 and 3a is flat. The section 4 and 4a includes two depressions 8' which surround the pivot point of the plier and is further provided with a compartmentalized hollow portion 6 and a jaw portion 7.

15 As may be seen in FIGS. 3 and 4 when the section 3 overlies the section 4 one of the depressions 8' and the inner surface of section 3 form a recess 8. The lower part of section 3 covers the hollow portion 6 and its upper part abuts the jaw portion 7. The jaw portion 7 20 serves as a mutual reinforcement for the coextensive sections 3 and 4 and 3a and 4a in the parts of the arms 1 and 2 which contact the objects which are to be worked on. In addition, the jaw portion 7 is used to attach accessory parts with which the pliers are to be provided.

25 In the embodiment shown the sections 3 and 4 and 3a and 4a are of a non-metallic substance such as synthetic plastic material preferably made by injection molding.

In the assembled condition the two sections 4 and 4a 30 are located in the middle of the pliers. The surfaces in which the compartmentalized hollow portions 6 are seen provided are directed toward one another in opposite directions. A depression 8' of section 4 abuts the identical depression 8' of the other section 4a. The section 3 overlies and covers the section 4, and the same is true of sections 3a and 4a. Thus the sections 3 and 3a are located on the outside of the pliers. The recesses 8' receive and pivotably guide a part of each section 4, 4a of the arms 1 and 2. The recess 8' of the arm 1 receives a part of section 4a of the arm 2 and the recess 8' of the arm 2 receives a part of section 4 of the arm 1. This interlocking and mutual guidance of the two arms provides the plier with a high degree of stability against distortion and misalignment.

45 In order to further increase the rigidity of the pliers the holes which are provided in each section of the pliers for the pivot pin 5 may be provided with a metallic insert 9.

The useful features of this invention are easily seen. 50 The individual sections 3 and 4 and 3a and 4a may be conveniently and inexpensively made of synthetic plastic material. The sections are simple to assemble into a plier which exhibits the rigidity heretofore only obtainable in metallic pliers.

55 Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

60 What is claimed as new and desired to be protected by Letters Patent is set forth in the appended

65 1. A plier, comprising a pair of crossed arms, one of said arms including a first section having two opposite

sides each provided with a recess located opposite a recess on the other side, the other of said arms also including a first section similar to that of said one arm, a part of each of said first sections being received and pivotable in a recess of the respective other first section, said arms each further including a second section coextensive with the respective first section and overlying and being connected to that side of the respective first section which faces away from the respective other first section; and pivot means connecting said parts of said arms for relative pivotal displacement of the latter.

2. A plier as defined in claim 1, wherein one of said second sections of each arm is flat and the first section of the same arm includes two portions, a compartmentalized hollow portion and a jaw portion.

10

15

3. A plier as defined in claim 2, wherein said first sections each have first surfaces which are directed toward one another, and second surfaces which face outwardly away from one another, and wherein the respective second sections each overlie one of said first surfaces.

4. A plier as defined in claim 1, wherein said pivot means includes a hole provided in each section, and wherein said holes are in registry and accommodate a reinforcement element.

5. A plier as defined in claim 1, wherein said sections are injection-molded elements composed of non-metallic material.

6. A plier as defined in claim 5, wherein said non-metallic material is a synthetic plastic material.
